[57] CLAIM

The ornamental design for a belt buckle ensemble, as shown and described.

DESCRIPTION

FIG. 1 is a top, front, right side perspective view of a belt buckle ensemble including buckle, belt loops and belt tip, showing my new design, the rear view thereof being unornamented;

FIG. 2 is a front elevational view thereof;

FIG. 3 is a top plan view thereof; and,

FIG. 4 is a bottom plan view thereof.
